SMOKING PIPE

Tokusaburo Mochizuki, San Francisco, Calif.

Application December 14, 1939, Serial No. 309,175

3 Claims. (Cl. 131—180)

This invention relates generally to improvements in smoking pipes and has particular reference to improvements in the bowl section of the pipe whereby at least two tobacco containing chambers may be formed in the bowl of said pipe.

Another object of the invention is to provide a smoking pipe of the character set forth whereby the smoke from the bowl to the smoker's mouth travels through a tortuous path, thereby cooling the smoke.

A further object of the invention is to provide a smoking pipe of this character which includes at least two tobacco containing chambers and means for alternately closing and opening these chambers, whereby the pipe may be filled and smoked from either chamber of the bowl.

A further object of the invention is to provide a smoking pipe of this character that includes 20 more than one tobacco containing chamber, one or both of which may be normally closed by a plate rotatably mounted upon the top of the bowl of the pipe, which chambers may be alternately covered or uncovered through the medium 25 of an opening in the plate, whereby either chamber of the bowl may be alternately opened.

30 A further object of the invention is to provide a pipe of this character having a bowl provided with a removable threaded chamber at its lower end, whereby the pipe may be thoroughly cleaned when desired.

Other objects and advantages will be apparent during the course of the following description.

In the accompanying drawing forming a part
35 of this specification and in which like numerals
are employed to designate like parts throughout
the same.

Fig. 1 is a side elevation of a pipe including my improved bowl and other elements constituting the invention;

Fig. 2 is a top plan view of the same, showing the bowl and its segregated chambers and portions of the plate being broken away;

45 pipe bowl and indicating the ducts leading to the stem of the pipe, as indicated by the line 3—3 in Fig. 2.

Fig. 4 is a transverse section of the bowl of the pipe, further illustrating the configuration thereof and the ducts formed therein; and

Fig. 5 is a top plan view per se of the pipe bowl and ducts formed therein, showing the particular arrangement of the tobacco chambers in the pipe bowl and the ducts connecting each of the chambers.

The invention resides primarily in a smoking pipe having the usual bowl 6 and stem 7. The bowl 6 is preferably provided with at least two tobacco containing chambers 7' and 8, and the lower end of the bowl of the pipe is provided with a screw threaded cap member 9 which encloses the lower end of the bowl. 5

The upper end of the bowl is covered by a plate 9' rotatably held in position by a screw 10, which screw 10 extends into a central part 11 10 formed in the bowl of the pipe. An additional rotatable plate 12 is mounted upon the plate 9' and is movable thereon for the purpose hereinafter specified.

Referring now to Fig. 2, it will be noted that 15
ducts 13 and 14 extend through the bottom sec-
tion of the bowl of the pipe and emerge in the
chamber formed in the cap member 9. These
ducts connect, respectively, the chambers 7' and
8 of the bowl. A duct 15 extends vertically 20
through the bowl of the pipe and communicates
with the chamber 16 and extends horizontally under
the plate 9', thence downwardly and to
the stem of the pipe, as indicated by the nu-
meral 17. 25

It will be observed that the rotatable plate 9' is provided with an opening 19 which may correspond with either the chamber 7' or the chamber 8, whereby the pipe may be filled with tobacco and smoked through either of the chambers, depending upon which way the plate is rotated. 30

The plate 12 is merely for the purpose of swinging about and covering the opening 19 in the plate 9' when the pipe is carried in the pocket of the smoker. 35

It will thus be noted that when nicotine collects in any section of the pipe or in the ducts thereof, the cap member 9 may be removed, which cap member 9 is threaded on the bowl as indicated at 18, and the plates 9' and 12 may also be removed by the removal of the screw 10. Therefore, all ducts may be opened for cleansing of the bowl by the introduction therein of any well-known pipe cleaning instrument. 45

Therefore it will be observed that a pipe of this character having a bowl employing two tobacco containing chambers which may be filled with tobacco and smoked alternately will greatly increase the smoker's comfort in that the smoke will be cooled and the pipe will not have to be refilled as often as has been the custom with the usual pipe. 50

Furthermore, it will be noted that the plate 12 may be swung from one side to the other when 55

a tobacco chamber is emptied to produce a proper draft through the stem from a filled chamber of the pipe.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In a smoking pipe of the class described including a bowl having chambers formed therein, a cap member closing the bottom thereof, a stem integrally formed with said bowl, ducts extending through said bowl and communicating with said chambers, and a swingable closure mounted upon the upper end of said bowl for alternately closing said chambers.
2. In a smoking pipe of the class described including a bowl having a plurality of tobacco containing chambers positioned therein, a screw

cap arranged on the lower end thereof and forming a chamber, a plate arranged upon the upper end of said bowl, a swingable element capable of alternately closing either of said chambers, ducts communicating with the interior of said cap and communicating with said chambers, and additional ducts arranged in said bowl and communicating with the interior of said cap, whereby smoke may be drawn from either of said chambers through the stem of the pipe.

3. In a smoking pipe of the class described including a bowl and an integrally formed stem, said bowl having at least two tobacco containing chambers formed therein and having a cap member closing the lower end thereof, ducts extending through the bottom of each of said chambers and communicating with a duct formed in the stem of the pipe, and means for closing the upper end of the bowl of the pipe, said means consisting of a swingable plate adapted to selectively control the draft from one or the other of the chambers of the pipe.

TOKUSABURO MOCHIZUKI.
